UNITED STATES PATENT OFFICE.

CHARLES H. PEIRSON AND WILLIAM A. BOHUE, OF PHILADELPHIA, PENNSYLVANIA,
ASSIGNORS TO E. F. HOUGHTON & CO., OF PHILADELPHIA, PENNSYLVANIA, A COR-
PORATION OF PENNSYLVANIA.

MACHINE FOR FORMING LUG STRAPS.

Application filed August 28, 1922. Serial No. 584,701.

To all whom it may concern:

Be it known that we, CHARLES H. PEIRSON and WILLIAM A. BOHUE, citizens of the United States, and residents of Philadelphia, Pennsylvania, have invented certain improvements in Machines for Forming Lug Straps, of which the following is a specification.

The object of our invention is to construct a machine for bending and forming lug straps of leather, or equivalent material.

Lug straps are used to connect the lug stick of a loom with the picker stick and are made of a series of strips of leather held together by glue, or other cementitious material.

In the accompanying drawings:

Fig. 1 is a view in elevation of our improved machine for forming lug straps;

Fig. 2 is a side view of the machine;

Fig. 3 is a vertical, sectional view;

Fig. 4 is a sectional plan view on the line 4—4, Fig. 3;

Fig. 5 is a sectional plan view on the line 5—5, Fig. 3;

Fig. 6 is a sectional plan view on the line 6—6, Fig. 3;

Fig. 7 is a perspective view of one of the wedges;

Fig. 8 is a perspective view of a lug strap formed by our improved machine; and

Fig. 9 is a sectional view of the lug strap.

Referring to the drawings, 1 is the back plate of the machine mounted on a channel member 1^a. 2 is the inside former for the lug strap, which is attached to a block 4 by bolts 3. The former 2 rests against the back plate 1 and the block extends through a slot 5 in the plate, as shown in Fig. 3. 5^a is an abutment at the upper end of the slot 5 and the block 4 is held against this abutment by a spring 6 secured to the block and to a pin on the channel member.

Mounted in bearings at the upper end of the back plate is a shaft 8 on which is a cam 7 having a handle 9. The cam rests against the upper end of the former 2. When the cam is turned, it forces the former 2 towards a fixed block 10 secured to the back plate and clamps a leather blank onto the block. The upper end 11 of the block 10 is curved to form the rounded end of the lug strap, and the lower end 12 of the former 2 is

curved to produce a curved surface on the inside of the lug strap, as shown in Fig. 9.

55

The block 10 is held in a fixed position by bolts 10^a, which extend through a slot in the plate 1.

18 is a cylinder secured to the back plate. In this cylinder is a plunger 17 having a piston 17^a. The plunger is attached to a cross head 16, which is arranged to slide on the back plate. In the present instance, the cross head has two arms 15, which slide on the back plate 1. The back plate has longitudinal slots 1^b. Extending through these slots are flanged guide strips 15^a, which are secured to the arms by screw bolts, or other fastenings. The arms are connected by upper and lower clips 16^a. Secured to the upper clip 16^a is a wear plate 14^b, which rests on the fixed block 10.

60

13, 13 are wedges, which are located on the inside of each arm 15. The inner surface of each arm is beveled, as shown in Fig. 1. Secured to each wedge is a stud 19, which passes through a slot 20 in its arm. On this stud is a spring 21 bearing against the outer surface of the arm and a nut on the stud and tending to hold the wedge 75

yieldingly to the arm. Secured to each stud is a coiled spring 22, which is attached to a pin 23 on an arm. The tendency of the spring 22 is to hold the wedges yieldingly 80

in the forward position. The plunger may be operated by air, water, or other fluid, under pressure. When fluid under pressure 85

is admitted to the cylinder by the pipe 18^a, the cross head—with its arms—is raised, and when the fluid is admitted to the cylinder by the pipe 18^b, at the upper end of the cylinder, the plunger is retracted. At the upper end of the machine are stops 24 in the form of screws, which limit the movement 90

of the wedges 13.

95

In operating the machine, the leather blank to be bent is made of a series of strips of leather held together by glue, or other cementitious material, in order to produce blanks of the proper thickness. The blank 100 is then introduced into the machine before the glue, or other cementitious material, sets. It is then placed on the block 10 and the former 2 is moved towards the block by operating the handled cam 7. The cam 105 causes the former 2 to clamp the blank

firmly onto the blank 10, which gives the blank the proper contour. The plunger 17 is raised, which causes the wedges 13 to turn the projecting ends of the strap against the sides of the former 2. When the wedges strike the screw stops 24, they remain in a fixed position while the plunger, and its arms, continue the forward movement. This movement forces the wedges towards the former 2 and the wedges firmly clamp the strap against the sides of the former. The parts remain in this position until the cementitious material sets, after which the blank can be retracted and the finished lug strap removed from the machine.

By using the wedges, the ends of the lug straps are not subjected to great pressure until the wedges are driven in contact with the stop screws. This prevents chafing and tearing of the leather.

We claim:

1. The combination in a machine for forming lug straps, of a back plate; a block thereon; a movable former; means for moving the former to clamp a blank against the block; a cylinder; a plunger mounted in the cylinder; a cross head on the plunger; and arms on the crosshead extending on each side of the block and arranged to bend the blank around the former as the plunger is raised.

2. The combination in a machine for forming lug straps, of a back plate; a fixed block thereon; a movable former for clamping a blank to the block; a cross head having arms extending on each side of the block; a wedge between each arm and the block; and means for moving the cross head.

3. The combination in a machine for forming lug straps, of a back plate; a block thereon; a sliding former mounted on the back plate; a spring tending to hold the former away from the block; a cam for forcing the former towards the block to clamp the blank thereon; a cylinder on the back plate; a plunger in the cylinder; a cross head on the plunger; arms on the cross head extending on each side of the

block, the inner surfaces of the arms being beveled; a wedge resting against the beveled surface of each arm; and means for holding the wedges yieldingly against their arms, the arms, with their wedges, bending a blank against the former when the plunger is raised.

4. The combination in a machine for forming lug straps, of a back plate; a block thereon; a sliding former mounted on the back plate; a cam for forcing the former towards the block to clamp a blank thereon; a cylinder on the back plate; a plunger in said cylinder; a cross head on the plunger; two arms extending from the cross head, the inner surface of each arm being beveled; a wedge resting against the beveled surface of each arm; means for holding the wedges yieldingly against the arms; and means for holding the wedges yieldingly in the forward position so that, when the plunger is raised, the arms will carry the wedges past the block, bending the blank and clamping the same against the former.

5. The combination in a machine for forming lug straps, of a back plate; a fixed block thereon; a movable former mounted above the block, the former and the block being shaped to curve the end of the lug strap; a spring for yieldingly holding the former; a cam for moving the former towards the block; a cylinder on the back plate; a plunger in said cylinder; a cross head on the plunger; slotted arms projecting from the cross head, the arms having their inner surfaces beveled; a wedge on the inner side of each arm, each wedge having a stud projecting through the slot in its arm; a spring on the stud yieldingly holding the wedge against the arm; a spring attached to each stud and to the arm tending to hold the wedges in the forward position; and adjustable stops to limit the movement of the wedges and to allow the arms to be raised independently of the wedges in order to force the wedges towards the former.

CHARLES H. PEIRSON.
WILLIAM A. BOHUE.
